UNITED STATES PATENT OFFICE.

FRANCIS STORM, OF PHILADELPHIA, PENNSYLVANIA, ASSIGNOR OF ONE-HALF HIS RIGHT TO GUSTAVIS STORM, OF SAME PLACE.

DESIGN FOR PERFUMERY-BOTTLE.

Specification forming part of Design No. 6,239, dated November 5, 1872.

To all whom it may concern:

Be it known that I, FRANCIS STORM, of the city and county of Philadelphia and State of Pennsylvania, have invented a Design for a Perfumery-Bottle, of which the following is a specification:

The nature of my design is fully represented in the accompanying photographic illustration, to which reference is made.

The body of the bottle represented in my design bears an exterior resemblance somewhat similar to that of a pyramid whose base is of a parallelogram form, with the exception that the neck terminates in a cylindrical form

instead of a point, as in a true pyramid. The bottle is further embellished with moldings, which extend around the edges and form panels or recesses on the sides of the glass, in one of which is a representation of the sun. That portion of the glass adjoining the neck is ornamented with lines which are raised and curved gracefully.

What I claim as my invention is—

The design for a perfumery-bottle, substantially as shown and described.

Witnesses: FRANCIS STORM.
